(57) **CLAIM**

The ornamental design for parts for cooling devices, as shown and described.

DESCRIPTION

The patent or application file contains at least one drawing executed in color. Copies of this patent or patent application publication with color drawing(s) will be provided by the Office upon request and payment of the necessary fee.

1.1 is a perspective view of a first part for cooling device.

1.2 is a front view of the first part for cooling device.

1.3 is a rear view of the first part for cooling device.

1.4 is a left side view of the first part for cooling device.

1.5 is a right side view of the first part for cooling device.

1.6 is a top view of the first part for cooling device.

1.7 is a bottom view of the first part for cooling device.

2.1 is a perspective view of a second part for cooling device.

2.2 is a front view of the second part for cooling device.

2.3 is a rear view of the second part for cooling device.

2.4 is a left side view of the second part for cooling device.

2.5 is a right side view of the second part for cooling device.

2.6 is a top view of the second part for cooling device.

2.7 is a bottom view of the second part for cooling device.
